[57] CLAIM

The ornamental design for a fuel filter cartridge, as shown and described.

DESCRIPTION

FIG. 1 is a top plan view of a fuel filter cartridge in accordance with the invention;

FIG. 2 is a front elevational view of the fuel filter cartridge of FIG. 1;

FIG. 3 is a bottom view of the fuel filter cartridge of FIG. 1;

FIG. 4 is a side elevational view of the fuel filter cartridge of FIG. 2 viewed from the right thereof;

FIG. 5 is a rear elevational view of the fuel filter cartridge of FIG. 2;

FIG. 6 is a side elevational view of the fuel filter cartridge of FIG. 2 viewed from the left thereof;

FIG. 7 is a top plan view of a second embodiment thereof, the bottom view is identical to FIG. 3;

FIG. 8 is a front elevational view of the second embodiment shown in FIG. 7, the rear view, the side view and the opposite side view are identical;

FIG. 9 is a top plan view of a third embodiment thereof; and,

FIG. 10 is a front elevational view of the third embodiment shown in FIG. 9, the rear view, the side view and the opposite side view are identical; the bottom view is identical to FIG. 3.

FIG. 1
